UNITED STATES PATENT OFFICE

154,936

DESIGN FOR A SINK STOPPER

Rollin J. Limbert, Norristown, Pa., assignor to Lee
Rubber & Tire Corporation, Conshohocken, Pa.,
a corporation of Pennsylvania

Application July 30, 1947, Serial No. 140,621

Term of patent 14 years

(Cl. D4—3)

To all whom it may concern:

Be it known that I, Rollin J. Limbert, a citizen of the United States, and a resident of Norristown, county of Montgomery, State of Pennsylvania, have invented a new, original, and ornamental Design for a Sink Stopper, of which the following is a specification, reference being had to the accompanying drawings, forming a part thereof, wherein:

Figure 1 is a perspective view of a sink stopper, showing my new design;

Figure 2 is a plan view of the bottom surface of said sink stopper;

Figure 3 is a plan view of the top surface thereof; and

Figure 4 is a transverse sectional view taken on the line 4—4 of Figure 2.

I claim:

The ornamental design for a sink stopper, as shown.

ROLLIN J. LIMBERT.
